ARTICLE HOLDER FOR VEHICLE SUN VISORS

Herbert S. Chase, Woodmere, N. Y.

Application December 20, 1956, Serial No. 44,287

Term of patent 14 years

(Cl. D14—6)

Figure 1 is a front elevational view of an article holder for vehicle sun visors, showing my new design in closed position,

Figure 2 is a side elevational view;

Figure 3 is a view similar to Figure 1, showing the holder for open maps in an open position, and

Figure 4 is a rear elevational view of Figure 1.

I claim:

The ornamental design for an article holder for vehicle sun visors, substantially as shown.
